WHEEL BALANCER

Johanness Norgaard, Chicago, Ill.

Application August 13, 1954, Serial No. 31,864

Term of patent 14 years

(Cl. D52—1)

Fig. 1

Fig. 2.

Fig. 3

Fig. 1 is a side elevational view of a wheel balancer showing my new design, the opposite side thereof being substantially the same in appearance;

Fig. 2 is a top plan view thereof; and

Fig. 3 is an end elevational view thereof.

The dominant feature of my design resides in the portion of the wheel balancer shown in full lines.

I claim:

The ornamental design for a wheel balancer, as shown and described.
